Primary Examiner — Susan Bennett Hattan
Assistant Examiner — Leanne Was(57) **CLAIM**

An ornamental design for a dispenser carrier, as shown and described.

DESCRIPTION

FIG. 1 is a perspective view of our invention;
 FIG. 2 is a front elevational view thereof, the rear elevational view being a mirror image thereof;
 FIG. 3 is a right side elevational view thereof, the left side elevational view being a mirror image thereof;
 FIG. 4 is a top plan view thereof; and,
 FIG. 5 is a bottom plan view thereof.

The dotted line representations of interior structures in FIG. 5 are for purposes of illustration only and form no part of the claim.

The dispenser carrier is used as part of an assembly that removably mounts a portable spray can for delivering insect repellent in a manner hung from a backpack, belt loop or the like, to facilitate outdoor use of the spray can.
